UNITED STATES PATENT OFFICE.

HOLMAN GOULD, OF AUBURN, MAINE.

DISPENSING-CAN.

SPECIFICATION forming part of Letters Patent No. 722,099, dated March 3, 1903.

Application filed September 4, 1902. Serial No. 122,116. (No model.)

To all whom it may concern:

Be it known that I, HOLMAN GOULD, a citizen of the United States, residing at Auburn, in the county of Androscoggin and State of 5 Maine, have invented a certain new and useful Dispensing-Can, of which the following is a specification, reference being had therein to the accompanying drawings.

This invention relates to dispensing-cans 10 adapted for delivering in suitable quantities any liquid, such as the various kinds of oils, including kerosene, naphtha, gasoline, and the like.

One of the principal objects of the present 15 invention is to produce a cheap, durable, and effective dispensing-can in which the important parts—such as the pump mechanism, pump-cylinder, and the air and oil pipes—are so constructed and arranged as to be readily 20 removable, thereby facilitating the repairing of the can and the several parts thereof. By these means the life of the can may be greatly increased and the can as a whole kept in repair at a nominal cost.

25 A further object of the invention is to so construct a can of the character described as to economize in the cost of production.

A further object is to provide reliable means for excluding water from the can either when 30 sitting upright or lying on a side and also preventing the escape of oil from the can.

With the above general objects in view the invention consists in the novel construction, combination, and arrangement of parts, as 35 hereinafter fully described, illustrated, and claimed.

In the accompanying drawings, Figure 1 is a 40 central vertical section through a dispensing-can constructed in accordance with the present invention, showing the same closed and ready for transportation. Fig. 2 is a horizontal cross-section on the line 22 of Fig. 1. Fig. 3 is a detail elevation showing the manner of fastening the cover on the top of 45 the can. Fig. 4 is an enlarged detail section showing the air-sink and the relation thereof to the can and the oil-pipe.

Like reference-numerals designate corresponding parts in all figures of the drawings. 50 Referring to the drawings, 1 designates the body of the can, which for the sake of cheap-

ness may be constructed of tin and by preference is of cylindrical shape, being closed at the top by a wall 2 and at the bottom by a wall 3, the bottom wall 3 being held at an 55 elevation by a flange 4, which may be formed by extending the cylindrical body of the can below the bottom 3, as shown in Fig. 1. The flange 4 provides room for the air and oil sinks, hereinafter described, and prevents 60 the same from coming in contact with any surface upon which the can may rest when standing upright.

The top 2 is provided with an opening 5, and the bottom 3 is provided with a similar 65 opening 6 in line with the opening 5, said openings being adapted to receive a pump-cylinder 7, which is preferably double, consisting of two thicknesses of tin or other material arranged one within the other and preferably in contact, as shown. The length of the cylinder is such that it extends entirely through the body of the can and also through the openings 5 and 6, projecting far enough below the bottom 3 to be soldered to the outside of the bottom, as indicated at 8. At the 75 top also the cylinder is soldered to the can and projects a considerable distance above the top of the can and is covered by a cap 9, having a surrounding flange 10, which extends down upon the outside of the projecting portion of the cylinder. The cap 9 rests directly on the top edge of the cylinder and reaches to or nearly to the top of the can, where it is provided with eyes 11 to receive 80 fastening devices 12, such as pieces of wire, which also connect with other eyes 13 on the top of the can, the cap 9 being thus securely held in place. The cap may, however, be readily detached by removing the tie-wire or 85 fasteners 12.

The cap 9 is provided with a central collar 14, which extends both above and below the body of the cap, as shown in Fig. 1, to provide a long bearing for the stem 15 of the pump and 95 also to form an effective closure for a vent-hole 16 in the stem 15, which is tubular throughout. The upwardly-projecting portion of the collar 14 is designed to enter a correspondingly-shaped recess 17 in the pump-handle 18, which is fastened upon the upper end of the stem 15 and closes that end of the 100

stem. When the pump is at the lowest end of its stroke, the upper portion of the collar 14 is received in the recess 17, and should the can be standing out in the rain no water can find its way into the pump-stem, as it will be stopped by said collar, taken in connection with the handle, which fits over the collar. On the lower end of the stem 15 is a piston 19 of any suitable construction. No valves are necessary in the construction of the pump, as by placing a finger over the vent-hole 16 and operating the pump the air passing in through the top of the pump-cylinder and by the piston 19 will be forced out of the lower end of the pump-cylinder, which is closed by the end wall 20, having an upstanding nipple 21, through which the air passes and by means of which any moisture or water or dirt which may possibly find its way into the cylinder is prevented from getting farther, the upstanding nipple 21 forming a trap.

Extending through the body of the can is an air-pipe 22, which is preferably of lead for the sake of durability and to prevent corrosion. The pipe 22 extends entirely through the can from top to bottom and also through the top and bottom 2 and 3 of the can and sufficiently beyond the same to be soldered or otherwise secured thereto, as shown at 23. By removing the solder 23 the pipe 22 may be removed from the can when needed for any purpose. Covering the lower end of the pump-cylinder and the lower extremity of the pipe 22 is an air-sink 24, which is detachably secured, as by solder, to the bottom 3, said sink serving to convey the air from the pump-cylinder to the air-pipe 22. Adjacent to the upper end of the pipe 22 the top of the can is provided with a small air-inlet hole 25, and a V-shaped tubular connection 26 is detachably connected, as by solder, to the top of the can, one end of the connection 26 covering the upper end of the pipe 22, while the opposite end of the connection covers the air-hole 25. Thus air compressed by the pump is forced through the pipe 22 into the upper portion of the can, so as to force the contents of the can outward through the discharge-pipe, hereinafter described. By making the air-inlet hole 25 quite small the air passes backward into and through the pipe 22 very slowly and to that extent assists the operation of the pump, the hole 25 acting somewhat in the manner of a check-valve. The connection 26 is provided intermediate its ends with an air-shut-off cock 27. An oil-pipe 28 also extends through the body of the can from top to bottom, corresponding exactly in length and manner of fastening with the air-pipe 22, said pipe 28 being preferably soldered, as shown at 29, to the top and bottom of the can. Adjacent to the lower end of the pipe 28 the bottom of the can is provided with an oil-hole 30, and said hole, together with the lower end of the pipe 28, is covered by means of an oil-sink 31, which, like the air-sink 24, is detach-

able for giving access to the pipe 28, the oil-sink being preferably soldered to the bottom of the can to facilitate its removal. Communicating with the upper end of the oil-pipe 28 is a discharge-nozzle 32, having an elbow 33, which fits over the upper discharge end of the pipe 28, the nozzle and its elbow being provided with a shut-off cock or valve 34, which is opened by turning the nozzle outward to the position shown in Fig. 1 and closed by turning said nozzle inward over the top of the can, under which latter adjustment the nozzle affords no projection beyond the side 80 of the can. The elbow 33 of the discharge-nozzle is sufficiently large to fit over the soldered upper extremity of the oil-pipe 28.

35 designates a raised collar surrounding the usual filling-point of the can, the same being closed by a filling-cap 36. It frequently happens that the filling-cap corrodes and is difficult to remove, and in order to overcome this and facilitate the removal of the cap a sleeve 37 is extended diametrically along the top of the cap and secured firmly thereto, so as to receive a pin or nail or other convenient implement which may be used as a lever or handle for turning the cap on or off.

In order to still further prevent the admission of water to the pump-cylinder, I make use of what may be termed a "pump-cover" 38 of a size and shape adapted to fit over and entirely inclose the upper end of the pump-cylinder, the pump-cap, and the handle, said cover being cylindrical in shape and closed at its upper end. At the lower edge the cover 38 is provided at one side with an eye 39, which connects with a staple 40 or its equivalent on the top of the can and forms a hinged joint. At the opposite side the cover 38 is provided with another eye 41 to receive a hook or other suitable fastener 42, connected with the top of the can. The cover is thus securely held in place for transportation, but may be readily thrown back in order to operate the pump.

In operation the cover 38 is thrown back and the pump is operated to compress air, the finger of the operating-hand being held over the vent-hole 16. The air is forced into the upper portion of the can, and the liquid is thereby forced upward into the pipe 28. By turning the nozzle 32 to the position shown in Fig. 1 the oil is forced outward through the nozzle and into the lamp or other receptacle placed beneath the same. If desired, while the nozzle 32 is closed any amount of air may be forced into the can and the shut-off cock 27 closed. This retains the air in the can, so that without doing any further pumping the discharge-nozzle may be swung outward, when the air-pressure will automatically force the oil outward through the nozzle.

The can is economical in construction and all parts are accessible for repairs. The pipes 22 and 28 are preferably of lead and will last indefinitely, while the pump-cylinder is double-walled, so that in case the outer wall

should rust or be eaten through the oil will be excluded from the pump-cylinder by the second inner wall.

Having thus described the invention, what I claim as new, and desire to secure by Letters Patent, is—

1. The combination with a dispensing-can having openings in the top and bottom thereof, of a removable pump-cylinder passing through both of said openings and extending entirely through the body of the can, a pump arranged in the cylinder, and a sink covering the bottom of the cylinder.
2. The combination with a dispensing-can having openings in the top and bottom thereof, of a double-walled pump-cylinder passing through said openings and extending entirely through the body of the can, a pump arranged in the cylinder, and a sink covering the bottom of the cylinder.
3. The combination with a dispensing-can, of a pump-cylinder arranged therein and passing through the bottom of the can, an air-pipe passing through the top and bottom of the can and communicating with the upper portion of the liquid-space, and a sink covering the lower end of the pump-cylinder and air-pipe and affording communication between said parts.
4. The combination with a dispensing-can, of a pump-cylinder arranged therein and passing through the bottom of the can, a removable air-pipe passing through the top and bottom of the can and communicating with the upper portion of the can, and a detachable sink covering the lower end of the pump-cylinder and air-pipe.
5. The combination with a dispensing-can, of a pump-cylinder passing through the body of the can and projecting above the top of the can, a removable flanged pump-cap fitting over the upper end of the cylinder and fastening means for the cap consisting of eyes on the cap and can and a flexible lacing, substantially as described.
6. The combination with a dispensing-can, of a pump-cylinder arranged therein and projecting over and above the top of the can, a cap on the upper end of the cylinder having

a centrally-arranged collar projecting above 50 and beneath the body of the cap, and a pump comprising a tubular stem provided with a vent in the side which lies within the collar when the stem is moved inward, and a handle on the stem recessed to receive a portion of 55 said collar.

7. The combination with a dispensing-can, of a pump-cylinder arranged within the can and projecting through the top and above the sides thereof, a cap fitted upon the upper end 60 of the cylinder, a pump-stem passing through the cap and having a handle at its upper end, and a cover fitting over and inclosing the top of the pump-cylinder, cylinder-cap and pump-handle and provided with means for securing 65 the same to the top wall of the can.

8. The combination with a dispensing-can having a small perforation in the top thereof, of a pump-cylinder and pump arranged within the can, an air-pipe leading through the 70 can and communicating at one end with the pump-cylinder and opening at the other end through the top of the can, and a tubular connection having one end arranged over the air-pipe and the other end over the small perforation in the top of the can, said tubular connection being provided with a shut-off cock.

9. The combination with a dispensing-can, having a small opening in the bottom thereof, of a pump arranged within the can and adapted 80 to compress air in the upper portion of the can, a liquid-pipe passing through the body of the can and through the top and bottom thereof, and connected by air-tight joints with the top and bottom of the can, a discharge-nozzle communicating with the upper end of said pipe, and an oil-sink attached to the bottom of the can and covering the lower end of the oil-pipe and of said opening in the bottom of the can, substantially as and for 85 90 the purpose described.

In testimony whereof I affix my signature in presence of two witnesses.

HOLMAN GOULD.
